COIN WRAPPER CRIMPING MACHINE

Clement Lee Downey, Cincinnati, Ohio

Application July 22, 1940, Serial No. 346,706

26 Claims.

(Cl. 93—5)

This invention relates to a coin wrapper crimping machine, the purpose of which is to close one end of a cylindrical paper wrapper containing a stack of coins arranged in face contact. Wrappers of the general type referred to are disclosed in United States Patent No. 2,205,283, issued to C. L. Downey on June 18, 1940. The machine of the present invention, however, will operate upon any more or less conventional form of wrapper which may require the closing of one end after having been charged with a stack of coins or similar objects.

One of the objects of the invention is to provide a coin wrapper crimping machine embodying means for the rapid production of completed coin-charged packages fed thereto in an incomplete or partially assembled condition.

Another object is to provide a machine of the character stated, which is simple, reliable, and free from the need of frequent attention or servicing.

A further object of the invention is to include, in a machine of this type, means for accurately counting the coin wrappers operated upon and for exposing any attempt on the part of the operator to run coin packages through the machine without registration thereof. Also, means are provided for rendering the machine inoperative as soon as a predetermined number of coin packages have passed therethrough.

Another object is the provision of an effective signal or warning mechanism designed to aid the operator in limiting the output of the machine to a predetermined maximum, as established by a setting of the machine prior to placing it in operation.

Another object of the invention is to provide in a machine of the character referred to, effective yet inexpensive means ensuring the operator against injury during operation of the machine, while at the same time effectively overcoming all efforts to jam the machine and impair the accuracy or the continued proper operation thereof as intended. The machine is thereby rendered foolproof and safe in operation.

Another object of importance is to provide a machine of the character stated, which may quickly be adapted for the crimping of coin wrappers of various diameters, that is, coin wrappers for the various denominations of coins in any money system.

The foregoing and other objects are attained by the means described herein and disclosed in the accompanying drawings, in which:

Fig. 1 is a front elevational view of the wrap-

per crimping machine, with the front cover plate and the top plate removed.

Fig. 2 is an enlarged cross-sectional view taken on line 2—2 of Fig. 1, showing a crimping head which forms a detail of the invention.

Fig. 3 is a top plan view of the machine as illustrated in Fig. 1 with the top plate omitted.

Fig. 4 is a plan view showing the forward portion of the Fig. 3 illustration as it appears upon removal of the transverse strut or reinforcing plate 4A, thereby to expose a carriage which forms part of the invention.

Fig. 5 is a fragmental cross-sectional view taken on line 5—5 of Fig. 1, showing details of the carriage.

Fig. 6 is a fragmentary cross-sectional view taken on line 6—6 of Fig. 1, and showing part of the mechanism for operating the crimping head.

Fig. 7 is a perspective view, slightly enlarged, illustrating one part of a self-adjusting gripper or clamp adapted to hold and release a coin-filled wrapper undergoing transfer by the carriage.

Fig. 8 is a wiring diagram utilized in electrically controlling the operation of the machine.

Fig. 9 is a plan view of a top plate for the machine, parts being broken away, and showing parts of the signal, counting, and controlling mechanisms which comprise the machine of the invention.

Fig. 10 is a fragmentary cross-sectional view taken on line 10—10 of Fig. 9.

Fig. 11 is an enlarged fragmentary cross-sectional view taken on line 11—11 of Fig. 9.

Fig. 12 is a cross-sectional view taken on line 12—12 of Fig. 9.

Fig. 13 is a perspective view of the machine.

For a proper understanding of the present invention, it is necessary to appreciate that the machine disclosed herein is adapted to operate upon a filled coin wrapper, which, by reason of a previous operation or manipulation, has been filled with coins and has had one of its ends closed or crimped to prevent passage of the coins from said closed or crimped end. The function of the instant machine, is that of accepting the filled coin wrapper, in the condition just mentioned, and operating upon the remaining open end for crimping it closed against the stack of coins held within the wrapper. The type of closure resulting from the operation of the machine, is very similar to that resorted to in finishing the slug end of a shot gun shell.

In brief, the machine comprises a suitable

cabinet which houses the mechanism, and which includes a top or cover plate 2, Fig. 9 of the drawings, and which will be referred to in regular order. The cabinet includes the side walls 3 and 5, which are spanned by a strut or plate 4A that supports a wrapper chute or guide 6, which is preferably in the form of a tube or well properly dimensioned to loosely receive a filled but unfinished coin wrapper fed into the open top 7 thereof either automatically or by hand. In descending through the chute or tube 6, the filled wrapper, with its upper end open, is directed onto a reciprocable carriage 8 which includes a clamp or holder that maintains the wrapper in an upright position, and thereafter, through the agency of a tripping means actuated by the wrapper in its descent, the carriage moves the upright wrapper to a position beneath a crimping head which at a proper moment descends upon the open end of the wrapper and crimps it to the closed condition. Thereafter, the carriage again shifts, and directs the completed or closed package to a discharge port through which the package is ejected from the machine.

The foregoing constitutes the cycle of operation of the machine, which is repeated each time that a filled open-ended wrapper is dropped into the chute or well 6, or is otherwise fed to the clamping means of the carriage.

The foregoing constitutes a very general statement of the machine operation, and does not include reference to various auxiliary devices and refinements that characterize the completed machine.

Referring first to Figs. 1 to 4 inclusive, it will be noted that the machine comprises a main shaft 10, the opposite ends of which are journaled in bearings 11 and 12 mounted upon the side walls of the cabinet. Upon the main shaft 10 there is rotatably mounted a worm wheel 13 and a driving clutch disc 14, these two parts being connected so as to rotate in unison. A worm wheel 15 on the motor shaft 16 drives the worm wheel 13 and the clutch disc 14. The motor M may be directly connected with the worm, for effecting a constant drive.

The upper end of shaft 16 is adapted to carry a fixed pulley 17 which, by means of a belt 18, drives a second pulley 19 which is fixed to the shaft 20 of the crimping head 9. The sleeve 21 of the crimping head has a spline connection with shaft 20, so that the head may be elevated and lowered while rotating with the shaft 20 that drives it. The character 211 indicates a gear case which may be charged with suitable lubricant for the worm and worm wheel.

It should be understood that the gear case and the bearings for shaft 16 are supported upon a bracket 22 fixed to the rear wall of the cabinet. A second bracket 23 carries the necessary bearing for the upper end of the rotatable shaft 20, and this bracket may be supported upon side wall 3 of the cabinet.

From the foregoing, it will be understood that so long as the motor M is energized, as it will be under normal circumstances, the crimping head will be rotated at high speed, while at the same time the driving clutch element 14 will rotate with the worm wheel 13 which is secured to its hub.

The driven clutch part 24, which is splined to shaft 10 for unitary rotation, is arranged to be engaged and disengaged from the driving clutch element 14 to determine the rotational

movements of the main shaft. Whenever the clutch 14-24 is engaged, a pair of cams fixed upon the main shaft, and indicated at 25 and 26, will be rotated to effect the transfer of the 5 wrapper to the crimping position, and to carry it from the crimping head to the discharge port.

The means provided for engaging the clutch elements, may consist of a compression spring 27 which at one end bears upon the face of cam 10 26, and at the other end bears upon the hub 28 of the horizontally shiftable clutch member 24, so that the spring tends always to yieldingly urge the clutch members into engagement. The hub 28 may carry a fixed stop or abutment 29 15 which is normally stopped by a shoulder 30 formed on a rocker arm 31 which has a pivotal connection with extending bracket 32. As will be understood, lifting of the rocker arm from engagement with the stop or abutment 29, will 20 permit spring 27 to urge the clutch elements into engagement for driving the main shaft 10. It will be understood also that a momentary lifting of the rocker arm 31, Fig. 3, will permit the engagement of the clutch elements. Shortly prior 25 to completion of a single rotation of the clutch elements, a cam face 34 of the rocker arm is struck by the stop 29, resulting in shifting the clutch element 24 to the right, to disengage the clutch in opposition to the force of the spring 30 27. In other words, tripping of the rocker arm will permit the clutch parts 24, 28 and 29 to move to the left, under the influence of spring 27, but before a full revolution has been completed, the abutment 29 will strike the inclined 35 face 34 of the rocker arm, to shift the driven clutch element to the right, against the resistance of spring 27, and thereby disengage the teeth 35 of disc 24 from the teeth 36 of disc 14. Shoulder 30 normally abuts the stop 29, as shown, to 40 maintain a disengaged relationship of the clutch elements.

The means for momentarily displacing the rocker arm from the clutch disengaging position, comprises an electromagnetic means, which may 45 be in the form of a solenoid 37, whose iron core 38 is retracted each time that the windings of the solenoid are energized by means of an electrical current. The outer end of the solenoid core carries a pivot pin 39 upon which is pivoted 50 a link 40 which, at 41, has a pivotal connection with one arm 42 of a bell crank lever pivoted at 43. The horizontal arm 44 of the bell crank lever has a free end 45 which may descend upon and depress the free end 46 of the rocker arm, 55 in opposition to the force of a spring 47, each time that the electromagnetic means or solenoid is energized momentarily.

As was previously stated herein, the movement of a filled open-topped wrapper through the tube or well 6, initiates the operation of the machine. This is accomplished by causing the wrapper to initiate the energization of solenoid 37, and to this end the tube or well is provided with a trip lever 48 which may be pivoted as at 49 to the body of the tube or well, and a portion 50 thereof is disposed within a slot provided in the wall of the well or tube. The portion 50 extends into the well or tube so as to be struck by a descending filled wrapper, so that the trip lever 48 will be moved about its pivot 49 against the force of a small spring 51, to cause a pin 52, which extends from the trip lever, to depress a switch button 53 of an electrical switch 54. The switch 54 is of the momentary contact type, and is open-circuited by spring means, as is customary. The

contacts 55 and 56 of switch 54 (Fig. 8) are wired in series with the winding of the solenoid 37, so that electricity from the leads 57 and 58 will pass through the solenoid winding upon each momentary closing of the contacts of switch 54. As seen in Fig. 8, the circuit comprises the conductors 57, 59, switch contacts 60 and 61, the contacts of switch 54, the solenoid winding 37, and the return conductors 62, 63, and 58. It will be seen also that the motor M is connected across the leads 57 and 58, so as to be constantly energized.

The switch 54 (Fig. 1) preferably is fixed upon an extension 64 of a bracket 65 which extends from the side wall 5 of the cabinet. This bracket supports other elements of the combination and which will be referred to later.

Up to this point in the description, it will be readily understood that the dropping of a filled wrapper, with its top open, into the guide or well 6, will by striking the trip lever 48 close the contacts of the switch 54 for energization of the solenoid 37, which in turn will momentarily lift the rocker arm 38 for effecting an engagement of the clutch disc, thereby to rotate the main shaft 10 with its cams 25 and 26 for carrying the wrapper through the crimping treatment and discharging it from the machine. The details of the mechanism for performing the crimping treatment will now be described.

As was previously stated, the filled wrapper in descending through the chute or well 6, drops vertically onto a reciprocating carriage 8 which is provided with holding means that grasp and clamp the leading or closed end of the filled wrapper. The carriage, through the medium of yoke lever 66 actuated by an irregular face of the cam wheel 26, is shiftable thereby for transferring the wrapper from the initial position beneath well 6 to a second position beneath the crimping head 9. For this purpose, the carriage is mounted for reciprocating horizontal movement along a stationary carriage bed 67 which may be furnished with a suitable guide rib or tongue 68 complementary to a groove in the carriage base, not shown. One end of the carriage carries a pivot bolt or the like 69, which as best seen in Fig. 5, furnishes a mounting for the free ends 70 and 71 of a pair of L-shaped jaw shifters which include the elongated fingers or extensions 72 and 73. The free ends 74 of said fingers preferably are rounded or tapered, so that bodily movement of the carriage to the left (Fig. 5) will cause the ends of the fingers to ride upon the convergent faces 75 of a stationary cam block 76 of the carriage bed 67. The ends of the fingers are constantly urged toward each other by means of a spring 77 (Fig. 4), the ends of which springs are secured to the studs 78 of a pair of brackets 79 and 80 each of which is fixed as at 81, to one of the elongated fingers or arms 72 and 73. Accordingly, it will be understood that each movement of the carriage to the left will cause the spring 77 to urge the fingers together about their common pivot 69, as the free ends 74 ride down the inclines of the stationary cam block 76. Conversely, movement of the carriage to the right will effect a separation of the fingers, against the force of spring 77, under the influence of the cam block faces.

To each of the elongated fingers 72 and 73, there is attached a jaw or holder, these being indicated at 81 and 82. Each jaw or holder includes a pair of angularly disposed faces 84 and 85, of suitable width for bearing against the

lower or leading end portion of a filled wrapper dropped to the clamp or holder through the well 6, or otherwise lodged therein.

The jaw parts 81 and 82 are so dimensioned as to receive between them a wrapper filled with coins of the largest denomination, when the fingers 72 and 73 are fully spread to their maximum extent by the cam block 76. When the fingers are permitted to converge, as will occur when the ends 74 are riding upon the cam inclines 75, the jaws will move with the fingers to reduce the size of the space between the jaws, so that wrappers containing coins of smaller denominations will be held between the jaws. In this manner, the clamp or holder is adapted for accommodating wrappers corresponding in diameter to the diameters of the various denominations of coins, without the need for manual adjustment. In other words, the jaws are self-adjusting for clamping and holding filled coin wrappers in an upright position, regardless of the diameters of the wrappers subjected thereto.

While it is immaterial what form of means is utilized for mounting the clamp jaws upon the fingers 72 and 73, there is shown by way of example herein a satisfactory connection for those parts. The connection comprises the way or groove 86 (Fig. 7) formed in the outer face of each jaw member, and an upstanding pin or stop 87 limiting the width of the groove at its middle section, so that space is provided between the pin or stop, and the wall 88 of the groove, for reception of a finger such as 72 or 73. In this respect, the jaws 81 and 82 may be identical, however, as indicated by Fig. 7, jaw 82 may include a pair of fixed straps 89 spaced apart so as to embrace the sides of the other jaw, as shown in Fig. 5. These straps perform only as a means of closing the rear and forward ends of the clamp or holder device, and they maintain the jaws in alignment at all positions of convergence of the fingers. By means of the construction illustrated, the jaws may have a rocking movement relative to their respective fingers.

Referring now to Fig. 4, attention is directed to the circular aperture 90, which constitutes the discharge port for coin packages that have been operated upon and completed in the machine. It will be seen that port 90, which is formed in the carriage bed 67, is not aligned with the opening established by the clamp jaws 81 and 82, and for that reason a filled wrapper which initially is placed within or drops into the jaws from the chute or well 6, will be unable to pass through the discharge port. Referring again to Fig. 4, it is to be understood that a filled wrapper inserted between the jaws will, by the first movement of the carriage, be carried to the left and will have its upper open end subjected to the crimping action of the crimping head 9. Thereafter, the carriage will move to the right, beyond the normal or initial starting position illustrated by Fig. 4, to align the space between the clamping jaws with the discharge port 90, so that the completed wrapper or coin package will drop through the discharge port and into the base of the cabinet, the clamping action upon the package having been released by outward spreading of the fingers 72 and 73 due to the camming action of the cam block 76. After the completed wrapper or coin package has dropped, the final movement of the carriage to the initial or normal position of Fig. 4, is effected by the cam wheel 26.

The action of the cam wheel 26 may readily be understood upon reference to Fig. 1, wherein

is illustrated an extension 91 on the yoke lever 66 at the opposite side of its pivot 92, said extension carrying a roller or other follower 93 adapted to ride upon the annular faces of the cam wheel. The Fig. 1 illustration shows the cam wheel in its initial starting position, at which the follower rests in a depression 94 of the cam, preparatory to ascending an incline 95 and riding upon a rather long track face 96, which results in swinging the yoke lever 66 for shifting the carriage 8 to the left, with the jaws directly beneath the crimping head 9. As the cam wheel 26 rotates through most of its movement, the cam encounters an extreme incline 97, which permits a rather powerful spring 98 to withdraw the carriage to the discharge position of the wrapper or coin package. The next movement is effected by the incline 99, which leads the follower onto an elevated cam track section 100, which is immediately ahead of the initial section 94. Although the incline 99 need not necessarily be as extensive as shown in Fig. 1, it is found that the provision of the cam section 100, affording an extra final movement of the carriage, assists in disengaging the clutch discs to the fullest possible extent. Accordingly, a type of clutch construction other than that herein disclosed, might render unnecessary the elevated cam section 100, so that the cam might ride from the base of section 97 directly onto the initial starting section 94.

The connection between the carriage 8 and the lower end of yoke lever 66, may be effected by means of suitable short links, as indicated at 101.

Figs. 1 and 6 illustrate an acceptable form of means for lowering the rotating crimping head onto the open upper end of the filled wrapper, during the period at which the wrapper is positioned beneath the head. Said means may comprise a carriage 102 which rotatably supports the crimping head sleeve 21, and which may be elevated and lowered by means of a gear segment 103, the teeth of which engage the teeth of a rack 104 fixed on the carriage. The gear segment referred to preferably is rockably mounted upon a stationary pivot 105, and has at its free end a roller or other follower 106 which rides upon the peripheral irregular face of cam wheel 25. By preference, though not of necessity, the downward movement of carriage 102 is effected by means of a spring 107, the opposite ends of which abut the top of the carriage and the overhanging arm or bracket 23 which is directly above it. The carriage 102, as most clearly illustrated in Fig. 4, is vertically slidable within the guide grooves 108. As should readily be understood, rotational movement of cam wheel 25 will result in allowing the gear segment to move under the downward force of spring 107, thereby lowering the carriage which carries with it the crimping head 9. The cam may be depended upon to limit the downward movement of the crimping head.

It may be stated at this time, that the crimping head 9 is preferably detachable from its driving shaft 20, and is replaceable by crimping heads having different diameters designed to accommodate the various diameters of filled coin wrappers. It is to be noted also that the wrapper chute or well 6 likewise is readily replaceable by chutes or wells of different inside diameters, for the same purpose. Thus, upon a requirement that the machine be utilized for operating upon a different size of coin wrapper, it is necessary only that the crimping head and the chute or well 6 be replaced with similar elements propor-

tioned to accommodate another size of wrapper.

The crimping head, as most clearly illustrated in Fig. 2, may consist of a series of segmental forming pieces 109 depending from the head and so arranged as to provide a socket for reception of the open upper end of a coin wrapper. The curved upper end 110 of each segmental forming piece 109 serves as a means to inwardly turn the end of the wrapper as the crimping head spins axially thereover. The character 112 indicates a series of splines whereby the crimping head is mounted upon its driving shaft 20 so as to rotate therewith, while at the same time permitting the elevating and lowering of the head with its carriage 102. Any suitable means may be provided for precluding, under normal conditions, any vertical movement of the head relative to the carriage. A very simple form of means for this purpose is indicated by the annular groove 113 in the crimping head sleeve 21, which groove may be entered by the end of a screw or other retaining device 114. The particular type of means employed for this purpose is immaterial to the invention, and may accordingly be designed in accordance with acceptable engineering practice.

Attention is now directed to the Fig. 9 drawing view, which illustrates a cover or top plate to be fitted bodily over and onto the top of the cabinet illustrated in Fig. 3. The cover or top plate carries on its upper surface a conventional type of counter 115 which records the number of operating cycles of the machine, and consequently the number of coin packages operated upon. Associated with the counter operating mechanism, is an interceptor in the form of a plate or flapper 116, for limiting or controlling the rate at which a succession of open-ended filled wrappers may be fed to the machine, this being accomplished by obstructing access to the wrapper guide or well 6 during the major portion of each operating cycle of the machine. The interceptor means functions also for interrupting or terminating the feed of wrappers into the machine, beyond the machine capacity, or beyond the amount for which the machine has been set.

The interceptor 116 may be supported upon an arm 117 which at its free end is provided with a gear 118 disposed about the pivotal mounting 119 for the arm. A gear segment 120, mounted upon a shaft 121 which is journaled in a pair of brackets 122 depending from the cover or top plate 2, has its teeth in engagement with the teeth of gear 118. On the shaft of gear segment 120, there is fixed an extension 123 which is in the path of movement of a trip lug 124, which lug may be fixed to any rotatable element on the driven side of the clutch, and preferably is carried by the carriage cam. When the lug 124 moves with the carriage cam 26, it strikes the extension 123 and, through the agency of the intermeshing gear teeth, the interceptor 116 will be elevated to expose the well or tube 6 so that a filled open-topped wrapper may be inserted therein. It should be understood that the trip lug 124 is located at such a position upon the carriage cam, that at the beginning of every cycle of movement of the cam, and while the machine is at rest, the flapper or interceptor 116 will be held in an elevated position substantially at right-angles to the plane of the top plate or cover 2. Accordingly, it should be understood that as soon as the clutch is engaged, the trip lug 124 will pass the extension 123 and thereby permit the interceptor to assume a closing position over the top of the well or wrapper guide 6.

In this connection, it should be understood that the power stroke of the trip lug is utilized in lifting the interceptor to the open position, and that closing thereof may be effected by gravity or, if desired, by a spring, so that there will be no danger of the interceptor injuring the fingers of the operator when it moves to the closed or well-obstructing position.

It will be found convenient to operate the counter lever 125 from a lever 126 on shaft 121, through the agency of a connecting link which may be in the form of a tension spring 127. The counter preferably is one which will register on the up-stroke of its actuating lever 125, and it will be seen that the up-stroke occurs following the movement of trip lug 124 past the extension 123. The arm 111 operates within an elongated slot 128 formed in the top or cover plate 2, and it will be seen that the spring 127 also extends through the top or plate.

From the foregoing, it should be evident that the interceptor and counter apparatus of Fig. 10 is operated but once during each cycle of the machine operation. Moreover, the interceptor remains in an obstructing relationship to the well opening throughout the major portion of the operating cycle of the machine, but is held in an inoperative or nonobstructing position so long as the machine is at rest. Accordingly, since the interceptor closes against the top of the well as soon as a wrapper has been placed within the well, there is no opportunity afforded for feeding more than one wrapper at a time into the well. The operating cycle of the machine is so rapid, however, that the machine will accept coin wrappers as rapidly as an operator can feed them by hand.

In addition to the counter and interceptor apparatus, the machine is provided with a metering device designed to limit the capacity of the machine according to the will of the operator. The metering device is illustrated by Figs. 9, 11 and 12. With reference to Fig. 9, 129 indicates a ratchet wheel mounted upon a stud 130 projecting downwardly from the under face of the cover or top plate, there being furnished a suitable means such as a spring 131 for urging the ratchet wheel always in a counter clockwise direction of rotation as viewed in Fig. 9. This ratchet wheel is furnished with a number of peripheral ratchet teeth as shown, which for purposes of illustration may total one hundred teeth. At varying distances from the center of the ratchet wheel, there is mounted upon said wheel a series of extending pins or lugs 133, 134, 135, and these may be located at definite positions with respect to certain ratchet teeth; for example, pin 133 may be at the twentieth tooth, pin 134 at the twenty-fifth tooth, and pin 135 at the fiftieth tooth of the ratchet wheel. At the one-hundredth tooth of the ratchet wheel there is fixed a radially extending bar or abutment 132, which in length equals or exceeds the combined diameters of the pins 133, 134 and 135. These pins or abutments, cooperating with the mechanism about to be described, may be utilized for limiting the output of the machine, as may be required.

The character 136 indicates a rocking lever pivoted at 137 upon a stud 138 (Fig. 11), which stud is shiftable within an elongated aperture 139 of the cover plate. The end of lever 136 nearest the ratchet wheel, carries an extending pin or abutment 140 which, upon shifting of the stud to various positions along the aperture 139,

may be placed in the path of movement of any one of the pins or abutments 133, 134, 135 or 132. The object of so shifting the lever and its pins 140, is to cause a selected one of the ratchet wheel pins or abutments to strike the pin 140 as the ratchet wheel is rotated in clockwise direction, so as to tilt the lever 136 and thereby move the switch arm 141 of an electrical switch 142. The function of the switch 142, as will be explained in detail later, is to stop the machine and energize a warning signal 143, as soon as the machine has operated upon a given number of coin wrappers. The character 144 indicates an elongated slot in the free end of lever 136, for keeping the lever in operating relationship to the switch arm 141 in all positions of adjustment of said lever 136.

To establish the proper adjusted positions for lever 136, there may be provided a frame or the like 145 on the upper or exposed surface of the top plate, said frame carrying a series of notches or stops 146 spaced apart in correspondence with the paths of travel of the ratchet wheel pins, thereby to enable a correct adjustment of the lever 136 and its pin 140, with respect to the paths of travel of the ratchet wheel pins or abutments. A lug or pointer 147 on the metering adjuster is adapted to engage any one of the notches 146 for establishing the location of the stop pin 140.

In the condition of the metering device, as illustrated by Fig. 9, intermittent rotation of the ratchet wheel in a clockwise direction, at each operating cycle of the machine, will bring the stop 132 around through a full rotation of the ratchet wheel, until at the one-hundredth tooth of the wheel the stop 132 will strike the pin 140, thereby to rock the lever 136 in a counter-clockwise direction about its pivot stud 138 to actuate the switch 142 and temporarily defunctionalize the machine. As will be evident, shifting of the pointer 147 to the second notch of the frame 145 would place the stop pin 140 in the path of travel of lug 135, so that the machine would be automatically stopped after having operated upon fifty wrappers. In like manner, disposition of the pointer 147 to the third notch would place the stop pin 140 in the path of movement of ratchet abutment 134, or, upon placing the pointer in the fourth notch, the stop pin would rest in the path of movement of ratchet abutment 133. It will be recalled that ratchet abutments 133 and 134 establish the location of the twentieth and twenty-fifth teeth, respectively, of the ratchet wheel so that operation of the machine would be limited to twenty or twenty-five cycles or crimping operations, depending upon the position of the stop pin 140 as determined by the pointer 147. An extra notch 1460, or a series of extra notches, may be furnished if desired, to dispose the stop pin 140 into the path of movement of any additional and intermediate ratchet wheel abutments, not shown.

In the event that the metering mechanism is to be rendered inoperative, so that continued uninterrupted operation of the crimping machine may result, there may be provided a means of latching the pawl release lever 149 to a position at which the pawls 150 and 151 will be withdrawn from their operative positions against the teeth of the ratchet wheel. The pawl release lever 149, which is movable about a pivot 152, and which may be limited in its movement by means of a stop 153, may be held in the pawl-retracted position by means of a button or other

latch element 154 that may be grasped and lifted after the lever has been rotated, to stand in the path of the lever and preclude the return thereof to the normal position of Fig. 9. It will readily be observed that the free ends 155 and 156 of the pawl release lever are operative against both pivoted pawls for disengaging them, upon a single rotational movement of the release lever in the clockwise direction. The pawl release is adapted to hold both pawls out of engagement at the same time, although one might release subsequently to the other. It should be noted that pawl 150 is furnished with any acceptable form of yielding means, such as a spring 157 which normally urges the pawl to the engaging position. The other pawl likewise may be furnished with a spring, for the same purpose.

In Fig. 11 is detailed the construction of the metering adjuster, and it is therein evident that the pointer 147 forms part of a cup-shaped sleeve having a flange 148 which may be grasped and moved axially of stud 138, in a direction for compressing the spring 158, until the pointer 147 is removed from a notch 146, whereupon the stud shaft 138 may be slid lengthwise of the elongated slot 139 as previously explained. The knob 159 of the stud shaft may furnish a stop for the axial movement of the sleeve flange 148, and the washer 160 maintains the assembly in unitary condition. It is to be understood that the shank of stud shaft 138 is flattened at opposite sides so that it may not rotate within the elongated slot 139, and that the sleeve whose flange is indicated at 148 likewise is fitted to the flat-sided shank for sliding movement without rotation. Thus, the pointer 147 is maintained always at right angles to the axis of the slot 139.

The pins indicated at 161 and 162 may be anchored in the top plate and properly located for limiting the rocking movement of lever 136. Lever 136 may be yieldingly maintained against the stop 162 by means of a spring 163.

Means are provided which advance the ratchet wheel tooth by tooth, in a clockwise direction of rotation (as viewed in Fig. 9), under normal operating conditions of the machine. Said means may constitute an oscillating lever 164 having one end pivoted upon the stud 130 and having its opposite end 165 movable from the Fig. 9 position to a position against a stationary stop 166. The free end of lever 164 carries the pivoted pawl 150, and as will be understood, each successive movement of the lever into contact with stop 166 will cause the pawl to rotate the ratchet wheel a distance of one tooth. The movement of lever 164 may be effected through the agency of a link 167 which is pivoted thereto at the location 168, said link to be actuated each time that the machine performs a crimping operation. As is most clearly illustrated in Fig. 12, the forward end of link 167 may be pivoted as at 169 to a rock lever 170 that has a pivotal mounting 171 upon a bracket 172 which depends from the under face of the cover or top plate 2. A lug or extension 173 on the rock lever is normally disposed in the path of movement of an operating finger 174 carried by any nearby rotational element on the driven side of the clutch. As suggested herein, the operating finger may be fixed to the driven clutch disc 24, so that each rotational movement of said clutch disc in the clockwise direction (Fig. 12), produces a rocking of the lever 170 which is translated into a longitudinal motion of link 167, said link in turn operating upon lever 164 to advance the pawl 150

75 a distance equal to a single tooth of the ratchet wheel. The pawl 151 is a holding pawl, which maintains the ratchet wheel in the advanced positions to which it is moved by the driving pawl 150, in opposition to the force of spring 131. From the foregoing, it will be understood that actuation of the pawl release lever 149 will disengage both pawls from the ratchet wheel teeth, and thereby permit the spring 131 to return the 10 ratchet wheel to the initial starting position of Fig. 9.

Assuming that the operator wishes to have the machine perform, say twenty-five crimping operations, he will lift the member 148 to disengage 15 the pointer from its present notch, and then shift it to the third notch 146, thereby to place the stop pin 140 of lever 136 in the path of movement of the ratchet wheel pin or abutment 134. By proceeding to drop the filled open-ended wrappers in succession into the tube or well 6, the machine will operate the driving pawl 150 to intermittently advance the ratchet wheel until the pin or abutment 134, at the twenty-fifth tooth, strikes the stop pin 140 and moves the lever 136 25 in counter-clockwise direction about its pivotal mounting at 137. This action results in throwing the actuating lever 141 of switch 142, for breaking the electrical circuit at 60-61 (Fig. 8), and establishing a closed-circuit condition of a 30 second pair of contacts 175 and 176. The breaking of the electrical circuit at contacts 60-61, renders ineffective the switch 54 of the tube or well, so that it will be impossible to energize the 35 solenoid or magnetic means 37 which normally initiates the clutch engagement at 14-24. Accordingly, the entire machine will thereby be rendered inoperative upon having performed the preselected twenty-five crimping operations, even though the driving motor M may remain in operation. With the breaking of the circuit at contacts 60-61, there is effected a closing of the 40 electrical contacts 175 and 176, which permits a flow of electricity from lead 57 through said switch contacts, through the signal device 143, and back to lead 58 by way of conductor 63. This results in energization of the signal means 143, which may be either a visible signal such as a lamp, or an audible signal of known character. The switch contacts 175-176 will remain closed, and contacts 60-61 will remain open, so long as the ratchet pin or abutment 134 maintains a tilted condition of lever 136 against the stop 45 161 (Fig. 9), by reason of impingement of said pin or abutment 134 against the pin 140 of the lever.

50 To condition the machine for subsequent operation, the operator need only to actuate the pawl release lever 149 to disengage both pawls 150 and 151, whereupon the spring 131 will rotate the ratchet wheel back to the initial starting position. In the initial starting position, the switch contacts 60-61 will be closed, and contacts 175-176 will be open, as illustrated by Fig. 8. In this condition of the electrical circuit, the filled coin wrappers will be effective for closing the switch 54 to restore the normal operating condition of the machine.

55 While it is immaterial what form of means is utilized for normally maintaining the pawl actuating lever 164 in its position of rest against its stop or limit pin 177 (Fig. 9), the spring 157 which is attached to the driving pawl 150 may be utilized in the performance of that function. If desired, of course, a separate spring for the lever 164 may be provided, the one requirement being

that some form of yielding means be employed to return the lug 173 (Fig. 12) to the path of movement of the actuator 174 after each displacing movement of the member 173 by actuator 174.

With reference to the counter as disclosed in Fig. 9, the character 178 indicates a re-setting handle or knob for normalizing the counter to the zero reading. Referring to the pawls 150 and 151, as shown on the same drawing view, the character 179 indicates the pivot upon lever 164 which carries the pawl 150, whereas the character 180 indicates a fixed pivot for holding pawl 151. A structural brace for the side walls of the cabinet is indicated at 181, Figs. 1 and 3.

The bottom of the machine cabinet preferably is open, so that a bag or other receptacle may be removably supported in position to receive the completed packages as they are released from the carriage and dropped through the discharge port 90.

As was stated earlier herein, the feeding of the filled open-ended wrappers to the machine may be either manual or automatic. In either case, best practice sometimes may call for elimination of the chute or well 6, with a direct deposit of such wrappers in the clamp or holder without the aid of guide means comparable to the chute or well herein disclosed. Thus, it is readily to be appreciated that the filled open-ended wrappers might be deposited in the clamp or holder successively without the intermediary of the chute or well, and the machine cycle initiated by means at the clamp or holder, corresponding to switch 54, or by a closing of switch 54 otherwise than by means of the wrapper. Actually, the switch 54 might be conveniently located for manual operation, or it may be actuated by a separate machine which feeds the wrappers to the clamp or holder. In a continuously operating crimping machine, neither the switch nor the guide need be furnished of necessity.

In conclusion, it is pointed out that many of the machine parts and their arrangements are capable of considerable modification, and the substitution of various equivalents within the bounds of accepted engineering practice in machine design, is seen to be readily applicable. It is to be understood, therefore, that the machine herein disclosed represents but one of many possible arrangements or combinations of constituents that may be utilized, in reducing the invention to a practical and useful form.

What is claimed is:

1. In a machine of the class described, the combination which comprises a guide into which are fed a succession of cylindrical open-ended wrappers each containing a stack of coins, means for closing an end of each wrapper, and means including a member within the guide positioned to contact an inserted wrapper, for actuating the wrapper end closing means.

2. In a machine of the class described, the combination which comprises a guide for receiving a succession of cylindrical wrappers each having a substantially closed end and an open end, and containing a stack of coins terminating near the open end of the wrapper, means operative upon the open end of the wrapper for deforming said open end to preclude loss of coins therethrough, and obstructing means for the guide operative during the period of operation of the deforming means aforesaid, to limit the rate at which a succession of cylindrical wrappers may be introduced into the guide.

3. In a machine of the class described, the combination which comprises a guide for receiving a succession of cylindrical wrappers each having a substantially closed end and an open end, and containing a stack of coins terminating near the open end of the wrapper, means operative upon the open end of the wrapper for deforming said open end to preclude loss of coins therethrough, obstructing means for the guide operative during the period of operation of the deforming means aforesaid, to limit the rate at which a succession of cylindrical wrappers may be introduced into the guide, and means incapacitating the machine for operation after the performance of a predetermined number of deforming operations.

4. In a machine of the class described, the combination which comprises a guide for receiving a succession of cylindrical wrappers each having a substantially closed end and an open end, and containing a stack of coins terminating near the open end of the wrapper, means operative upon the open end of the wrapper for deforming said open end to preclude loss of coins therethrough, obstructing means for the guide operative during the period of operation of the deforming means aforesaid, to limit the rate at which a succession of cylindrical wrappers may be introduced into the guide, means incapacitating the machine for operation after the performance of a predetermined number of deforming operations, and a counter operating in synchronism with the guide obstructing means, for indicating the number of such operations performed.

5. In a machine of the class described, the combination which comprises a guide for receiving a succession of cylindrical wrappers each having a substantially closed end and an open end, and containing a stack of coins terminating near the open end of the wrapper, a reciprocable carriage including a clamping means located normally directly beneath the guide to receive and hold the substantially closed end of the wrapper after the latter has been dropped through the guide, a crimping head disposed above the carriage and to one side of the guide, for operating upon and deforming the open end of the wrapper to preclude the loss of coins therethrough, power means for reciprocating the carriage from the normal position stated, to a position at which the clamping means supports the wrapper end in aligned relationship with the crimping head, means controlled by each wrapper prior to entering the clamping means, for initiating reciprocation of the carriage and the operation of the crimping head upon the wrapper end, and means for releasing and discharging a crimped wrapper from the clamping means upon completion of each crimping operation.

6. In a machine of the class described, the combination which comprises a guide for receiving a succession of cylindrical wrappers each having a substantially closed end and an open end, and containing a stack of coins terminating near the open end of the wrapper, a reciprocable carriage including a clamping means located normally directly beneath the guide to receive and hold the substantially closed end of the wrapper after the latter has been dropped through the guide, a crimping head disposed above the carriage and to one side of the guide, for operating upon and deforming the open end of the wrapper to preclude the loss of coins therethrough, power means for reciprocating the car-

riage from the normal position stated, to a position at which the clamping means supports the wrapper end in aligned relationship with the crimping head, means controlled by each wrapper prior to entering the clamping means, for initiating reciprocation of the carriage and the operation of the crimping head upon the wrapper ends, means for releasing and discharging a crimped wrapper from the clamping means upon completion of each crimping operation, a metering device to selectively limit the number of successive crimping operations, of the machine, and means to selectively disable the metering device for continuous and uninterrupted operation of the machine.

7. In a machine of the class described, the combination which comprises a guide for receiving a succession of cylindrical wrappers each having a substantially closed end and an open end, and containing a stack of coins terminating near the open end of the wrapper, a reciprocable carriage including a clamping means located normally directly beneath the guide to receive and hold the substantially closed end of the wrapper after the latter has been dropped through the guide, a crimping head disposed above the carriage and to one side of the guide, for operating upon and deforming the open end of the wrapper to preclude the loss of coins therethrough, power means for reciprocating the carriage from the normal position stated, to a position at which the clamping means supports the wrapper end in aligned relationship with the crimping head, means controlled by each wrapper prior to entering the clamping means, for initiating reciprocation of the carriage and the operation of the crimping head upon the wrapper end, and means for releasing and discharging a crimped wrapper from the clamping means upon completion of each crimping operation, and an interceptor operative upon reciprocation of the carriage toward the crimping head, for obstructing the wrapper receiving guide until the carriage returns to its initial position beneath said guide.

8. In a machine of the class described, the combination which comprises a guide for receiving a succession of cylindrical wrappers each having an end to be crimped, a rotational crimping means located at a distance from the guide, and means including a carriage movable between the guide and the crimping means, for transferring the wrappers to the crimping means in succession, said carriage including a pair of opposed shiftable clamping jaws normally spaced apart to receive between them one end of a wrapper when introduced thereto through the wrapper guide, means operative upon movement of the carriage toward the crimping means, for shifting the clamping jaws one toward the other to grasp said end of the wrapper and secure it against rotation under the influence of the crimping means, and for releasing said wrapper end upon movement of the carriage away from the crimping means, and means for clearing the clamping jaws in readiness for reception of a subsequent wrapper introduced through the wrapper guide.

9. In a machine of the class described, the combination which comprises a guide for receiving a succession of cylindrical wrappers each having an end to be crimped, a rotational crimping means located at a distance from the guide, and means including a carriage movable between the guide and the crimping means for transferring the wrappers to the crimping means in

succession, said carriage including a pair of opposed shiftable clamping jaws normally spaced apart to receive between them one end of a wrapper when introduced thereto through the wrapper guide, means operative upon movement of the carriage toward the crimping means, for shifting the clamping jaws one toward the other to grasp said end of the wrapper and secure it against rotation under the influence of the crimping means, and for releasing said wrapper end upon movement of the carriage away from the crimping means, means for clearing the clamping jaws in readiness for reception of a subsequent wrapper introduced through the wrapper guide, and means obstructing access to the wrapper guide while the wrapper undergoing treatment is held by the clamping jaws.

10. In a machine of the class described, the combination which comprises a guide for receiving a succession of cylindrical wrappers each having an end to be crimped, a rotational crimping means located at a distance from the guide, and means including a carriage movable between the guide and the crimping means, for transferring the wrappers to the crimping means in succession, said carriage including a plurality of self-adjusting and self-centering clamping jaws accommodating wrappers of various diameters, said jaws being normally dilated to receive one end of a wrapper introduced thereto through the wrapper guide, means operative upon movement of the carriage toward the crimping means for yieldingly contracting the jaws upon said end of the wrapper and securing it against rotation with the crimping means, and means operative upon movement of the carriage away from the crimping means, to release the jaws and discharge the crimped wrapper.

11. In a coin wrapper crimping machine, the combination of a tubular upright wrapper guide, and a support for displaceably mounting said guide for substitution by similar guides of different internal diameters, whereby to accommodate coin-filled wrappers of different diameters to be dropped through said guides, a carriage including a self-adjusting clamping means located beneath the guide to receive one end of a cylindrical wrapper projected thereto in upright position through the guide, a rotary replaceable crimping means located at a distance from the guide and adapted for substantially closing that end of the wrapper which is opposite to the end received by the clamping means, means for reciprocating the carriage to dispose the clamping means and the wrapper held thereby in an operative relationship to the crimping means, and means for releasing the wrapper and discharging it from the clamping means upon completion of the crimping operation, said crimping means being replaceable with a similar crimping means complementary to the size of wrapper guide utilized for directing the wrappers to the clamping means.

12. In a coin wrapper crimping machine, the combination of a tubular upright wrapper guide, and a support for displaceably mounting said guide for substitution by similar guides of different internal diameters, whereby to accommodate coin-filled wrappers of different diameters to be dropped through said guides, a carriage including a self-adjusting clamping means located beneath the guide to receive one end of a cylindrical wrapper projected thereto in upright position through the guide, a rotary replaceable

crimping means located at a distance from the guide and adapted for substantially closing that end of the wrapper which is opposite to the end received by the clamping means, means for reciprocating the carriage to dispose the clamping means and the wrapper held thereby in an operative relationship to the crimping means, and means for releasing the wrapper and discharging it from the clamping means upon completion of the crimping operation, said crimping means being replaceable with a similar crimping means complementary to the size of wrapper guide utilized for directing the wrappers to the clamping means, and means including an electrical control common to the various sizes of substitute wrapper guides, for initiating the movements of the carriage by the dropping of a wrapper through a wrapper guide and into the clamping means carried by the carriage.

13. In a coin wrapper crimping machine, the combination of a tubular upright wrapper guide, and a support for displaceably mounting said guide for substitution by similar guides of different internal diameters, whereby to accommodate coin-filled wrappers of different diameters to be dropped through said guides, a carriage including a self-adjusting clamping means located beneath the guide to receive one end of a cylindrical wrapper projected thereto in upright position through the guide, a rotary replaceable crimping means located at a distance from the guide and adapted for substantially closing that end of the wrapper which is opposite to the end received by the clamping means, means for reciprocating the carriage to dispose the clamping means and the wrapper held thereby in an operative relationship to the crimping means, and means for releasing the wrapper and discharging it from the clamping means upon completion of the crimping operation, said crimping means being replaceable with a similar crimping means complementary to the size of wrapper guide utilized for directing the wrappers to the clamping means, means including an electrical control common to the various sizes of substitute wrapper guides, for initiating the movements of the carriage by the dropping of a wrapper through a wrapper guide and into the clamping means carried by the carriage, an interceptor for barring the feeding of additional wrappers into the guide so long as the clamping means contains a wrapper, and means for maintaining a displaced condition of the interceptor for permitting access to the guide at all other times.

14. In a machine for crimping an end of a coin wrapper containing a stack of coins, the combination which comprises: a guide for directing the coin wrapper, a movable carriage upon which the wrapper is deposited under the directional influence of the guide, and a crimping means located remote from the guide in line with the carriage travel for subjecting to the crimping means the wrapper carried by the carriage, power means including an engageable and disengageable clutch associated with the carriage for impelling the latter toward and from the crimping means, means including a trip in the path of movement of a wrapper passing along the guide, for engaging the clutch to initiate a cycle of carriage movement toward and from the crimping means, and means operated by a driven part of the clutch for precluding a feed of wrappers to the guide throughout substantially the entire movement cycle of the carriage.

15. In a machine for crimping an end of a coin wrapper containing a stack of coins, the combination which comprises: a guide for directing the coin wrapper, a movable carriage upon which the wrapper is deposited under the directional influence of the guide, and a crimping means located remote from the guide in line with the carriage travel for subjecting to the crimping means the wrapper carried by the carriage, power means including an engageable and disengageable clutch associated with the carriage for impelling the latter toward and from the crimping means, means including a trip in the path of movement of a wrapper passing along the guide, for engaging the clutch to initiate a cycle of carriage movement toward and from the crimping means, a metering device for selectively limiting the capacity of the machine, and signal means operated by said metering device for indicating attainment of the limit of capacity preselected.

16. In a machine for crimping an end of a coin wrapper containing a stack of coins, the combination which comprises: a guide for directing the coin wrapper, a movable carriage upon which the wrapper is deposited under the directional influence of the guide, and a crimping means located remote from the guide in line with the carriage travel for subjecting to the crimping means the wrapper carried by the carriage, power means including an engageable and disengageable clutch associated with the carriage for impelling the latter toward and from the crimping means, means including a trip in the path of movement of a wrapper passing along the guide, for engaging the clutch to initiate a cycle of carriage movement toward and from the crimping means, and means for precluding a feed of wrappers to the guide during the movement cycle of the carriage, a metering device for selectively limiting the capacity of the machine, signal means operated by said metering device for indicating attainment of the limit of capacity preselected, and means under the control of the operator for restoring the metering device to starting position and conditioning the machine for subsequent operation.

17. A machine for crimping an end of a coin wrapper containing a stack of coins, and which comprises the combination of a guide for directing coin wrappers in succession, a movable carriage upon which the wrappers are deposited singly under the directional influence of the guide, and a driven crimping head including means for reciprocating same toward and from a wrapper supported by the carriage, said crimping head being located remote from the guide and in line with the carriage travel, to place the wrapper in position to be crimped, power means including a single-rotation clutch associated with the carriage for impelling the latter toward and from the crimping head axis, a trip in the path of movement of a wrapper passing along the guide, an electromagnetic clutch engaging means, an electrically energizable signal, and three electrical switches each including a pair of contacts, the first of said switches being a normally open-circuited momentary contact switch arranged to have its contacts closed by the trip aforesaid each time that a wrapper enters the guide, a metering device for limiting the capacity of the machine and including means for normally maintaining a closed-circuit condition of the contacts of the second switch, an electrical circuit including a

source of electricity, and having connected in series relationship the contacts of the first and second switches and the electromagnetic means of the clutch engager, an electrically energizable signal, and a second electrical circuit including in series connection the source of electricity, the signal, and the third switch of the group, said third switch being normally open-circuited at its contacts, and means operated by the metering device upon reaching its preselected limit, for substantially simultaneously breaking the circuit of the second switch and closing the circuit of the third switch, to render the first switch and the electromagnetic means inoperative while at the same time energizing the signal, and means associated with the metering device for restoring the normal condition of the metering device and of the electrical switches and circuits aforesaid.

18. In a machine of the class described, the combination which comprises a clamp including normally distended jaws for holding cylindrical wrappers each having a substantially closed end and an open end, and containing a stack of coins terminating near the open end of the wrapper, a shiftable carriage carrying the clamp and all its jaws, a crimping means for operating upon the open end of the wrapper and forming it to a retaining condition substantially upon the coin stack, means for bodily shifting the carriage and the clamp between a wrapper charging location and the crimping means, means maintaining a contracted condition of the clamp jaws upon the wrapper during the major portion of the carriage movement, and means for distending the clamp jaws and effecting discharge of the crimped wrapper from the clamp upon completion of the crimping operation.

19. In a machine of the class described, the combination which includes a shiftable clamp for receiving and gripping the closed end of a cylindrical wrapper having a closed end and an open end, and which contains a stack of coins terminating near the open end of the wrapper, a rotary crimping head located remote from the shiftable clamp but in position to be aligned axially with the wrapper held thereby upon shifting of the clamp from the receiving position, means operative to so shift the clamp as it grips the closed end of the wrapper, and means operative subsequently to an initial shifting movement of the clamp in a direction away from the crimping head, to release the grip of the clamp from the wrapper end preparatory to a discharging motion of the wrapper.

20. In a machine for closing one end of a coin wrapper that contains a stack of coins resting upon the opposite closed end of the wrapper, said machine comprising a movable carriage movable from a wrapper receiving position to a crimping position and then to a discharging position, a self-adjusting clamp carried by the carriage and adapted to receive the closed end of the filled wrapper while the carriage assumes a position of rest at the receiving position, means operative for moving the clamp and the carriage to the several positions in the order stated, and means operative incident to moving of the carriage, for maintaining a gripping action of the clamp upon the wrapper end while the carriage moves from the receiving position to the crimping position and toward the discharging position, and for releasing the gripping action whenever the carriage assumes either the receiving position or the discharging position.

21. In a machine of the class described, the

combination which comprises a crimping means for an end of a cylindrical wrapper, and a carriage including a wrapper clamp movable toward and from the crimping means, for transferring wrappers to the crimping means in succession, said clamp being movable bodily with the carriage and comprising opposed shiftable jaws normally spaced apart to loosely receive the wrapper, means operative upon movement of the carriage toward the crimping means, for shifting the clamp jaws one toward another to grasp said wrapper and secure it against displacement by the crimping means, and for separating the jaws to release the wrapper upon movement of the carriage away from the crimping means, and means for clearing the clamp jaws in readiness for reception of a subsequent wrapper to be crimped.

22. In a machine of the class described, the combination which comprises a crimping means for an end of a cylindrical wrapper, and a reciprocable carriage including a wrapper clamp movable toward and from the crimping means, for transferring wrappers from a charging location to the crimping means in succession, said clamp being mounted in its entirety upon the carriage and constituted of opposed shiftable jaws normally spaced apart to loosely receive the wrapper, means for reciprocating the carriage and contracting the jaws upon the wrapper, to dispose the clamp and the wrapper held thereby in an operative relationship to the crimping means, and means for distending the clamp jaws, releasing and discharging the wrapper upon completion of the crimping operation, and returning the carriage and the clamp to the charging location for reception of a subsequent wrapper between the jaws as normally distended.

23. In a machine of the class described, the combination which comprises a crimping means for an end of a cylindrical wrapper, and a reciprocable carriage including a wrapper clamp movable toward and from the crimping means, for transferring wrappers from a charging location to the crimping means in succession, said clamp being mounted in its entirety upon the carriage and constituted of opposed shiftable jaws normally spaced apart to loosely receive the wrapper, means for reciprocating the carriage and contracting the jaws upon the wrapper, to dispose the clamp and the wrapper held thereby in an operative relationship to the crimping means, and means for distending the clamp jaws, releasing and discharging the wrapper upon completion of the crimping operation, and returning the carriage and the clamp to the charging location for reception of a subsequent wrapper between the jaws as normally distended, and means including an electrical control for initiating each cycle of movement of the carriage incident to feeding a wrapper to the clamp jaws.

24. In a machine of the class described, the combination which comprises a crimping means for an end of a cylindrical wrapper, and a carriage including a wrapper clamp movable toward and from the crimping means, for transferring wrappers to the crimping means in succession, said clamp being movable bodily with the carriage and comprising opposed shiftable jaws normally spaced apart to loosely receive the wrapper, means operative upon movement of the carriage toward the crimping means, for shifting the clamp jaws one toward another to grasp said wrapper and secure it against displacement by the crimping means, and for separating the jaws

to release the wrapper upon movement of the carriage away from the crimping means, means for clearing the clamp jaws in readiness for reception of a subsequent wrapper to be crimped, and means operative for barring a feed of wrappers into the machine throughout substantially the entire movement cycle of the carriage.

25. In a machine of the class described, the combination which comprises a crimping means for an end of a cylindrical wrapper, and a carriage including a wrapper clamp movable toward and from the crimping means, for transferring wrappers to the crimping means in succession, said clamp being movable bodily with the carriage and comprising opposed shiftable jaws normally spaced apart to loosely receive the wrapper, means operative upon movement of the carriage toward the crimping means, for shifting the clamp jaws one toward another to grasp said wrapper and secure it against displacement by the crimping means, and for separating the jaws to release the wrapper upon movement of the carriage away from the crimping means, means for clearing the clamp jaws in readiness for reception of a subsequent wrapper to be crimped, and a metering device for selectively limiting the machine to a predetermined number of carriage movement cycles.

26. In a machine of the class described, the combination which comprises a crimping means for an end of a cylindrical wrapper, and a carriage including a wrapper clamp movable toward and from the crimping means, for transferring wrappers to the crimping means in succession, said clamp being movable bodily with the carriage and comprising opposed shiftable jaws normally spaced apart to loosely receive the wrapper, means operative upon movement of the carriage toward the crimping means, for shifting the clamp jaws one toward another to grasp said wrapper and secure it against displacement by the crimping means, and for separating the jaws to release the wrapper upon movement of the carriage away from the crimping means, means for clearing the clamp jaws in readiness for reception of a subsequent wrapper to be crimped, means including a metering device for limiting the machine to a predetermined number of carriage movement cycles, means operative for indicating attainment of the limit of operations selected, and means under the control of an operator for restoring the metering device to starting position and conditioning the machine for subsequent operation.

CLEMENT LEE DOWNEY.
